CLAIM

The ornamental design for a robot airbag, as shown and described.

DESCRIPTION

This application is related to U.S. Design application Ser. No. 29/630,341, filed on even date herewith.

The file of this patent contains at least one drawing/photograph executed in color. Copies of this patent with color drawing(s)/photograph(s) will be provided by the Office upon request and payment of the necessary fee.

FIG. 1 is a color photograph of a front elevation view of our new robot airbag design, wherein the robot airbag is in an unactivated state and is not illuminated.

FIG. 2 is a color photograph of a front elevation view of our new robot airbag design, wherein the robot airbag is in an activated state and is not illuminated.

FIG. 3 is a color photograph of a front perspective view of our new robot airbag design, wherein the robot airbag is in an activated state and is not illuminated.

FIG. 4 is a color photograph of a right-side elevation view of our new robot airbag design, wherein the robot airbag is in an activated state and is illuminated green.

FIG. 5 is a color photograph of a right-side perspective view of our new robot airbag design, wherein the robot airbag is in an activated state and is illuminated green.

FIG. 6 is a color photograph of a front elevation view of our new robot airbag design, wherein the robot airbag is in an activated state and is illuminated red.

FIG. 7 is a color photograph of a right-side perspective view of our new robot airbag design, wherein the robot airbag is in an activated state and is illuminated red.

FIG. 8 is a color photograph of a right-side elevation view of our new robot airbag design, wherein the robot airbag is in an activated state and is illuminated red.

FIG. 9 is a color photograph of a front elevation view of our new robot airbag design, wherein the robot airbag is in an activated state and is illuminated; and,

FIG. 10 is another color photograph of a front elevation view of our new robot airbag design, wherein the robot airbag is in an activated state and is illuminated.
